UNITED STATES PATENT OFFICE

2,440,324

MOUNTING BRACKET FOR INSTRUMENT CASES

Clinton A. Blakelee, Middlebury, Conn., assignor to The Bristol Company, Waterbury, Conn., a corporation of Connecticut

Application December 8, 1943, Serial No. 513,413

1 Claim. (Cl. 248—27)

1

The invention relates to a mounting bracket adapted more especially to the mounting of an instrument case with respect to a panel for the same. The customary manner of securing an instrument case to a panel either for front-of-panel mounting or for flush mounting has been, in the former instance, through the use of perforated lugs on the case, which is usually a casting or a stamped or fabricated case, the lugs being bolted to holes provided in the panel. In the flush arrangement of mounting, a broad flange is provided at the front of the case and has holes therein through which to bolt the case to the panel through corresponding holes drilled in the panel near the edge of the "cut-out" or opening of the panel, the lugs then being omitted. Generally, the two types of mounting necessitate actual differences in the case as cast or otherwise fabricated.

An attempt was made (see U. S. Patent #1,859,-872 granted May 24, 1932, to T. R. Harrison) to obviate the requirement for different types of fittings by providing a removable lug which may be located on the case in any one of several manners adapted for three different types of mounting. The arrangement, however, is suitable only for the so-called "wall mounting," and for the flush mounting of the case special and different fittings are required. Thus, two distinct types of fittings must be furnished in many instances when shipping an instrument, as it is not known beforehand which type of mounting would be adopted when the instrument is to be installed. Only one set of the fittings would then be used, and the other discarded; or, having been supplied originally with a set for a particular mounting, should the customer subsequently desire to change to the other type of mounting, he would require different fittings.

An object of the present invention is to provide a novel mounting member or bracket whereby to secure an instrument case to a panel alternatively flush with the face thereof or upon the front of the panel to project from the same.

A further object of the invention is to provide a mounting bracket which is suitable for use with either a stamped or fabricated sheet metal case or with a cast or otherwise constructed case.

A still further object of the invention is to provide a bracket member whereby the case may be displaced from the edge of the "cut-out" or opening of the panel within which the case extends and whose edge is frequently irregular or rough; also, to obviate the necessity for drilling of bolt or like holes about the "cut-out" which material-

ly weaken the wall portion surrounding the mounted casing.

Another object of the invention is to provide a simple mounting member wherein, when utilized for mounting the case upon a panel or wall, the arrangement is such as to distribute the stress between the periphery of the case and the panel or wall and to provide a displacement or space between the back of the case and said panel or wall to accommodate screw and bolt heads or other projections on the case, as well as irregularities on the panel surface.

Still another object of the invention is to provide a bracket which, when installed to mount an instrument case flush with a panel, cannot twist or turn.

A further object is found in the provision of a mounting bracket which not only supports, but reinforces, the case of an instrument to which it is applied.

The invention has for an object, also, to provide a mounting bracket which, when utilized to mount an instrument case substantially flush with the panel, will remain invisible from the front of said panel.

A further object of the invention is to provide a strong, simple, and relatively inexpensive bracket member suitable for effecting the desired mountings.

30 In carrying out the invention, the novel bracket is constructed in the form of a T-element with outer surfaces of its flanges flush with each other or lying in the same plane, the intermediate portion of the T-element extending at right angles to these flanges and having a plane surface associated with an inner surface of one of the flanges parallel to the common plane of the outer surfaces, the plane surface of the intermediate portion being juxtaposed to said parallel inner surface and normal thereto. The two flanges, one of which preferably is longer than the other, as well as the intermediate portion, are perforated to receive respectively securing members whereby to mount an instrument case

40 on a panel or wall. The construction is such that the outer surfaces of the flanges, which lie in a common plane, may contact alternatively the outer surface of the instrument case or the outer face of a panel or wall for attachment of the bracket thereto. In the former instance, the intermediate portion retains a securing member which is in the nature of a set screw designed to contact the inner face of the panel and draw the inturned edge of a case flange into contact with the outer face of said panel to clamp

2

the case thereby in position substantially flush with said outer face of the panel. One of the flanges then extends into the panel opening for the case forwardly to the said flange of the case and between the periphery of said case and the panel. This will prevent turning or twisting of the bracket when installed, the same being attached to the said periphery of the case through the perforation in the shorter of the flanges.

For mounting the case on the front face of the panel or wall to project outwardly therefrom, both the intermediate portion and one of the flanges are attached to the periphery of the case, whereby the corner of the same is embraced and reinforced, while the other one of the flanges is secured to the panel.

The nature of the invention, however, will best be understood when described in connection with the accompanying drawings, in which:

Figs. 1 and 2 are vertical sections of a panel, with instrument case and bracket indicated in elevation, showing respectively an instrument case mounted substantially flush with the outer face of a panel or wall and projecting therefrom.

Figs. 3 and 4 are fragmentary longitudinal sections, on an enlarged scale, illustrating the manner of securing the instrument case according to the showings indicated in Figs. 1 and 2, respectively.

Fig. 5 is a similar view illustrating a modification in the flush type of case mounting by means of the novel bracket.

Fig. 6 is a perspective view of the novel mounting bracket, and Fig. 7 is a vertical section thereof.

Referring to the drawings, 10 designates a section of a panel or a wall member upon which an instrument case 11 is designed to be mounted, either flush with the front face 12 of the panel, as indicated in Fig. 1 of the drawings, or to project outwardly from this face of the panel, as indicated in Fig. 2 of the drawings. In accordance with the invention, this is effected by means of a novel form of mounting bracket, indicated more particularly in Figs. 6 and 7 of the drawings, the number of brackets utilized depending on the size of the case, four ordinarily serving the purpose.

The novel bracket is in the nature of a T-element having the flanges 15 and 16 with intermediate portion 17 extending at right angles thereto. The outer surfaces 18 and 19 of the flanges are flush or lie in a common plane; and one of the flanges, as the flange 16 which also is preferably shorter than flange 15, is provided with a perforation or hole 20. Similarly, the flange 15 is provided with a perforation 21 but in this instance the perforation is somewhat elongated and countersunk at the outer surface 18, as at 22.

The inner surface 23 of the flange 16 is substantially parallel to the outer surface 19 and at right angles to the juxtaposed surface 24 of the intermediate portion 17 of the bracket. This intermediate portion is also provided with a perforation 25 which is threaded. A pair of reinforcing integral webs 26 are located at the sides of the intermediate portion to connect the same with one of the flanges, in the present instance the shorter flange 15.

In adapting this bracket in the mounting of an instrument case in either of the positions indicated in Figs. 1 and 2, the two flange surfaces 18 and 19 will contact, in the flush mounting, the outer surface of the casing, and in the projecting

mounting, the outer face of the panel. This is more clearly indicated in Figs. 3 and 4, respectively; and suitable securing means are provided to retain the bracket to the case and panel, in accordance with the location of said case relative to the panel. Thus, a combined nut and bushing 30 may be provided in the case wall at the forward portion as by staking, soldering, or brazing the same thereto, and the nut is threaded to receive a cap bolt 31 passing through the perforation 20 of the flange 15, Fig. 3. In this embodiment of the invention, the flange 16 is not secured to the case wall but extends outwardly through an opening 32 of the panel beyond its outer face 12 substantially to an upturned and rearwardly directed flange 33 of the instrument. This not only reinforces the case wall but will avoid any twisting or shifting of the bracket particularly in securing its flange 16 to said wall. It will also serve to displace the outer surface of the case wall from the edge of the opening or "cut-out" 32 of panel which may be irregular or rough, and any projections from the case wall may be accommodated.

The intermediate portion 17 projects outwardly then from the flanges substantially parallel to the inner face 34 of the panel and, by means of a set screw 35 fitting the threaded opening 25, is caused to engage said face 34 and draw thereby the flange 33 into contact with outer face 12 to clamp the case to the panel with the said case substantially flush with the outer face 12 of said panel.

Or, as indicated in Fig. 5, particularly when the case is of cast metal or is molded, it may be so constructed that no threaded openings are required in its wall for retaining the bracket member thereto. Thus, the case 40 is shown as provided with a series of pockets or recesses 41, open at the outer end and arranged in the outer surface of the wall, said recesses extending from the inturned flange 42 inwardly a sufficient distance to accommodate the bracket flanges 15 and 16 which seat with the inner end of the former flange abutting the back wall 43 of the recess. When screw 35 is then turned in the intermediate portion 17 to clamp the flange 42 to panel 10, the tendency for the bracket to be rotated in a clockwise sense will cause the flange portion 16 to be brought into forcible engagement with the inner edge of the opening 32 in the panel, while at the same time sufficient stress will be exerted against wall 43 at the inner end of the recess 41 to hold the bracket firmly in its location in said recess without other means of attachment to the case, and also through the clamping action on flange 42 to firmly locate the case with respect to the panel.

When it is desired to mount the case on the panel to project outwardly therefrom, as indicated in Fig. 4, the flange 16 and the intermediate portion 17 are attached over the rear of the case, the portion 17 by means of a further combined nut and bushing 50 attached to the case and cooperating cap bolt 51, the latter preferably being "undersize" so as not to engage the threads within the opening 25; and the flange 16 by an additional combined nut and bushing 52 attached to the rear of the case and a screw 53, the head of which fits the countersunk portion 22. The elongated conformation of the countersunk opening 21 provides a certain tolerance in spacing between the part 52 and the flat perpendicular surface of the case 11, whereby is eliminated the need for precise dimensioning between the same. Flange 15 is secured directly to the front face of

the panel 18 by means of a bolt 34 and nut 35. In this instance, also, the wall of the case will be displaced by the interposition of the flanges from the outer face 12 of panel 18 to accommodate any irregularities or projections thereon; and at the same time, the flange 16 and the intermediate portion 17, angularly embracing the corner of the casing, will provide substantial support and reinforcement therefor.

The novel bracket member therefore serves for either type of mounting so that it is necessary to furnish merely one type of bracket member when shipping an instrument, and no waste is involved in the event that a change in the manner of mounting is subsequently desired. The said bracket is of simple construction, strong and relatively inexpensive to manufacture, and is suitable for use with either the cast type of case or the stamped or fabricated type of case. In the former, it will be necessary merely to drill and tap the case at the desired locations, or provide recesses therein; and in the latter, it is preferred to reinforce the wall, for example, by means of the combined nut and bushing hereinbefore described.

I claim:

The combination with a panel provided with an opening, and an instrument case adapted for mounting within said opening, said case having a front upturned flange; of a mounting bracket for securing the case to the panel in the opening thereof substantially flush with its outer face, said bracket comprising a T-element with oppositely directed perforated flanges and an intermediate portion at right angles thereto and

provided with a threaded perforation, the outer surfaces of said last-named flanges lying in a common plane and the inner surface of one of the flanges in a plane parallel to said common plane, the inner and outer surface of the one flange being adapted to fit in the panel opening between the panel and the case and extend forwardly of the face of said panel to the flange of said case, the other flange of the bracket being adapted to be secured to the case, and a screw adjustable in the perforation of the intermediate portion of the T-element to engage the inner face of the panel and draw the case flange into contact with the said outer face of the panel when the T-element has been secured to said case.
